UNITED STATES PATENT OFFICE.

SILAS D. WILLS, OF FORT PAYNE, ALABAMA.

FAN.

1,173,908.

Specification of Letters Patent. Patented Feb. 29, 1916.

Application filed February 12, 1915. Serial No. 7,775.

To all whom it may concern:

Be it known that I, SILAS D. WILLS, a citizen of the United States, residing at Fort Payne, in the county of Dekalb and State of Alabama, have invented new and useful Improvements in Fans, of which the following is a specification.

This invention relates to improvements in fans and has particular application to motor driven fans.

In carrying out the present invention, it is my purpose to provide a device of the class described which will be found especially useful as a ceiling fan and wherein the fan blades may be elevated and lowered so that the distance between the fan blades and the floor of the room or other compartment in which the fan is installed may be varied.

It is also my purpose to provide a motor driven fan which will embrace the desired features of simplicity, efficiency and durability, which may be installed and maintained at a minimum expense and which will operate effectively for its intended purpose.

With the above and other objects in view, the invention consists in the construction, combination and arrangement of parts hereinafter set forth in and falling within the scope of the claims.

In the accompanying drawings; Figure 1 is a view in side elevation of a fan constructed in accordance with the present invention, the same being shown as suspended from a ceiling. Fig. 2 is an enlarged vertical central sectional view through the fan. Fig. 3 is a cross sectional view on the line 3-3 of Fig. 2 looking in the direction of the arrow. Fig. 4 is a similar view on the line 4-4 of Fig. 2. Fig. 5 is a like view on the line 5-5 of Fig. 2. Fig. 6 is an enlarged vertical sectional view through the driving motor for the fan.

Referring now to the drawings in detail, 1 designates a ceiling plate which is substantially rectangular in contour and is formed, adjacent to the corners thereof, with openings 2 through which securing screws or bolts are adapted to pass in order to fasten the plate to the ceiling. In the present instance, an auxiliary supporting bracket 3 is suitably secured to the marginal edges of the ceiling plate and projects outwardly therefrom and is formed with openings 4 through which bolts or securing screws may be passed to coöperate

with the bolts in the openings 2 and so effectively secure the plate 1 to the ceiling.

Connected with the central portion of the plate 1 and depending therefrom is a tube 5 and formed on the lower end of the tube 5 and projecting outwardly therefrom is an annular flange 6 having the under surface thereof provided, adjacent to the inner edge thereof, with an annular groove 7.

Bolted or otherwise fastened to the flange 6 at the periphery thereof and depending therefrom is an annulus 8, while formed on the lower edge of the annulus 8 and extending inwardly therefrom is a circular flange 9.

Seated upon the flange 9 within the annulus 8 is a disk 10 formed centrally with an opening registering with the opening in the flange 9 and suitably connected to the wall of the opening in the disk 10 is a sleeve 11 projecting below the flange 9 and disposed coaxial with the tube 5. In the present instance, the confronting faces of the flange 9 and disk 10 are formed with coöperating grooves providing a race way to receive anti-friction bodies 12, while the adjacent surfaces of the flange 6 and the disk 10 are formed with coacting grooves providing a race way to receive anti-friction bodies 13 whereby friction between the annulus 8 and flange 9 thereon and the disk 10 in the rotation of the latter is avoided.

Within the axially alining sleeve 11 and tube 5 is a shaft 14 and connected with the lower end of the shaft and radiating therefrom are fan blades 15, while threaded through the sleeve 11 and spaced apart equal distances about such sleeve are set screws 16 whereby the sleeve may be fixed to the shaft 14 to rotate therewith and revolve the same within the tube 5. In the present instance, the upper end of the shaft 14 is formed with an upwardly extending axial stem 17 and threaded onto the stem 17 is a nut 18 having the outer edge thereof formed with a groove alining with a groove in the adjacent end of the shaft 14 to form a way designed to receive anti-friction bodies 19, the anti-friction bodies 19 engaging the inner wall of the tube 5 and acting to hold the shaft properly centered within the tube and minimize friction between the upper end of the shaft and the tube.

Suitably fastened to the upper surface of the flange 6 at one side of the tube is a spring motor 20 which is preferably in the

form of a clock train and includes a horizontal main shaft or arbor 21 upon which is rotatably mounted a sleeve 21 carrying a driving gear 22 working within a slot 5 formed in the adjacent portion of the flange 6 and meshing with an annular row of teeth 23 formed on the upper surface of the disk 10 concentrically thereof. Also keyed upon the sleeve 21' is a pinion 24 meshing with a gear wheel 25 keyed upon a power shaft 26. Surrounding the power shaft 26 is a spring 27 having the inner end thereof secured to the shaft and the outer end fastened to the adjacent face of a winding wheel 28 having 10 the periphery thereof formed with a groove 29 within which is fastened one end of a winding cord 30 extending upwardly and trained over a guide sheave 31 surrounding the tube 5 and secured to the ceiling and in- 15 closing the ceiling plate and the connection between such plate and the tube, the free end of the cord 30 being disposed within convenient reach of the occupant of the room or other compartment in which the fan 20 is installed. The action of the spring 27 upon the main sleeve 21' is controlled through a suitable form of governor 33 so that the main shaft will rotate at a uniform speed.

In the present instance, the governor 33 embodies spring arms 34 having corresponding ends thereof fastened to one end of the sleeve 21' and the remaining end fastened to a collar 35 surrounding the shaft 21 and capable of rotary and longitudinal movements thereon, and a collar 36 fixed upon the shaft 21 adjacent to the collar 35 between the latter and the adjacent end of the sleeve 21'. These spring arms 34 are equipped with weights 36' respectively and in the rotation 40 of the sleeve 21' under the action of the spring the weights 36' fly outwardly and so slide the collar 35 toward the collar 36 and in the event of the too rapid rotation of the sleeve 21' the collar 35 will engage the collar 36 and so act as a friction brake to cut down the speed of the sleeve.

In practice, when it is desired to set the shaft 14 in motion so that the fan blades 15 will be rotated to facilitate the circulation 50 of air, a pull is exerted upon the lower end of the cord 30, thereby rotating the winding wheel 28 and placing the spring 27 under tension. When the cord is released, the power spring reacts, and so rotates the power 55 shaft 26 and the sleeve 21', the governor 33 controlling the rotation of the sleeve from the spring. In the rotation of the sleeve, the gear wheel 22 imparts movement to the disk 10 thereby revolving the latter upon the flange 9 and within the annulus 8 so as to 60 rotate the sleeve 11 and the shaft 14 connected with such sleeve. To elevate or lower the fan blades, the set screws 16 are loosened

and the shaft 14 moved longitudinally within the tube and sleeve to dispose the fan 65 blades at the proper elevation, the set screws being tightened succeeding the proper adjustment of the blades.

The power shaft 26 is preferably provided with a crank handle 34 whereby the spring 70 may be placed under tension in the event of failure of the cord 30 or winding wheel 28.

In the present instance, I have shown my improved motor driven fan as embodied in a ceiling fan and in this connection I wish 75 it to be understood that the invention in its useful application is not limited to ceiling fans as the same may be incorporated in wall fans and other stationary fans.

While I have herein shown and described 80 one preferred form of my invention by way of illustration, I wish it to be understood that I do not limit or confine myself to the precise details of construction herein described and delineated, as modification and 85 variation may be made within the scope of the claims without departing from the spirit of the invention.

I claim:

1. A fan comprising a shaft, blades radiating from one end of said shaft, a sleeve encircling said shaft, an adjustable connection between said sleeve and shaft whereby the blades may be moved toward and away from the sleeve, a disk surrounding said 95 sleeve and fixed thereto, a flange supporting said disk, an annulus carrying said flange, anti-friction bearings between said disk and flange and annulus, means supporting said annulus, a motor carried by said last means, 100 and driving connections between said motor and disk.

2. A ceiling fan comprising a vertical tube, a flange on the lower end of said tube projecting outwardly therefrom, an annulus depending from the marginal edge of said flange, a flange formed on the lower edge of said annulus and extending inwardly therefrom, a disk within said annulus and resting upon the flange thereon, anti-friction 110 bearings between said last flange and annulus, a sleeve carried by said disk and depending below the second-named flange and coaxial with said tube, a shaft within said sleeve and extending into the tube, a connection between said shaft and sleeve, blades radiating from the lower end of said shaft, 115 a motor, and driving connections between said motor and disk whereby the sleeve and shaft may be rotated.

In testimony whereof I affix my signature in presence of two witnesses.

SILAS D. WILLS.
